F. J. CARMAN

MANUFACTURE OF OXIDATION PRODUCTS OF HYDROCARBONS

Filed Aug. 6, 1923

UNITED STATES PATENT OFFICE.

FRANCIS J. CARMAN, OF NEW YORK, N. Y.

MANUFACTURE OF OXIDATION PRODUCTS OF HYDROCARBONS.

Application filed August 6, 1923. Serial No. 656,085.

This invention relates to manufacture of oxidation products of hydrocarbons; and it relates more particularly to processes in which hydrocarbons are halogenated and the halogen derivatives oxidized, most advantageously with the aid of suitable catalysts, but not necessarily so, under conditions favoring production of the desired oxidation products from the hydrocarbons. More specifically, the invention relates to the manufacture of aldehydes, and particularly formaldehyde, by processes of this general character.

The principles of the invention are believed applicable to limited oxidation of hydrocarbons generally, and in its broader aspects the invention is therefore to be viewed as not restricted to the treatment of any specific class or series of hydrocarbons. Its greatest present utility is in the manufacture of aldehydes from aliphatic hydrocarbons, particularly the paraffin series of hydrocarbons, and specifically in the manufacture of formaldehyde from methane. Accordingly the manufacture of formaldehyde from methane will be more particularly hereinafter referred to and described as an illustrative example by means of which a full understanding of the principles underlying the invention may be afforded.

It is to be understood, however, that other hydrocarbons, not necessarily aliphatic but characterized by the presence of one or more paraffin radicals or groups in the molecule, are susceptible of treatment in accordance with the invention to produce useful products of limited oxidation, especially aldehydes.

Attempts have been made heretofore to produce intermediate oxidation products of the paraffin or saturated hydrocarbons by reacting directly thereupon with oxygen, but the difficulty is that oxygen does not react with them except at temperatures where it also reacts too vigorously with the desired final products for any appreciable yields of the latter to be recovered. Thus it is that, in the manufacture of formaldehyde, for example, present commercial methods are of quite a different type not involving the use of methane itself.

It is a principal object of the present invention to enable intermediate oxidation products of hydrocarbons to be obtained by oxidizing said hydrocarbons under such conditions as to render the oxidation suscepti-

ble of regulation and control, whereby the desired oxidation products are recoverable in substantial quantities, thus making possible the commercial production of intermediate oxidation products of the character described, using the parent hydrocarbons themselves as starting material, and thus avoiding the use of more costly derivatives which must be relied upon as starting material in processes heretofore known. A further and more specific object of the invention is to enable formaldehyde to be manufactured directly from methane or gaseous mixtures, such as natural gas, containing methane.

With the foregoing objects in view, as well as others which will become apparent as the disclosure proceeds, the invention comprises the novel process and process steps hereinafter disclosed and explained in connection with a specific illustrative example to which, however, it is to be understood the invention in its broader aspects is not restricted.

Generally described, the process of the invention comprises a carefully controlled and regulated oxidation of hydrocarbons, in the course of which oxidation the hydrocarbons pass through, or may be considered to pass through, a transition stage in which they exist in halogenated form as the result of what may be termed an initial oxidation. Further oxidation results in splitting off the corresponding hydrogen halid and producing the desired intermediate oxidation product of the particular hydrocarbon in question; while oxidation of the hydrogen halid regenerates the halogen which can be used to halogenate more of the hydrocarbon and thus maintain a cyclical process. In the case of manufacturing formaldehyde from methane, and assuming that the halogenating agent employed is chlorine, the process may be represented, for purposes of explanation, by the following reactions:

Within the scope of the invention as viewed in its broader aspects, these reactions may be carried out separately and in the order indicated. But it is of great advantage in practice to carry out all three reactions simultaneously or substantially so, especially when this is done with the aid of

a catalyst as will be more fully hereinafter pointed out. It is to be understood that in speaking of carrying out these reactions simultaneously, it is not intended to assert 5 that the chemical action as it actually occurs necessarily follows the precise reactions here given, these merely representing in a convenient manner one way of explaining what takes place. The exact mechanism of the 10 chemical reactions occurring when the process is carried out in practically one stage, instead of in the three stages represented by the above explanatory reactions, may be more or less complex and cannot readily be 15 determined with certainty. Furthermore the reactions by which the intermediate oxidation product is obtained are in practice accompanied to a greater or less extent by side-reactions such as further chlorination to 20 polychlor-derivatives, and oxidation of these and of formaldehyde and other oxygen derivatives to carbon monoxid, carbon dioxid and water.

By proceeding in accordance with the invention as generally set forth above, the desired oxidation of the hydrocarbon starting material may be effected at relatively low temperatures and is susceptible of reasonably accurate control and regulation; with 30 the result that it is possible to produce and recover substantial yields of the desired intermediate oxidation products from the reaction gases.

The initial oxidation of the hydrocarbon 35 by halogenation can be effected quickly and quantitatively at comparatively low temperatures, the extent of the halogenation depending upon the relative concentrations of the gases, the action of light, and the 40 presence or absence of catalysts, as well as on the temperature. The symmetry of the hydrocarbon molecule having once been broken, the resulting compounds are then much more readily susceptible to the action 45 of oxygen. Accordingly, by initiating the oxidation of the hydrocarbon through chlorination, for example, and then treating the resulting chlorine derivative with oxygen to produce the desired oxygen derivative, such 50 oxygen derivative can be obtained from the hydrocarbon without at any time exceeding relatively low operating temperatures, thus permitting recovery of good yields of said oxygen derivative. The hydrogen chlorid 55 split off in oxidizing the chlorine derivative may be wholly or largely oxidized to regenerate chlorine for re-use in chlorinating more of the hydrocarbon. By causing these 60 several operations to occur simultaneously, a certain proportion of chlorine will therefore suffice for the resultant oxidation of more of the hydrocarbon than corresponds to the proportion of the primary chlorine derivative consumed.

65 A concrete example illustrating how the things, this obviates the necessity for han- 130

process of the invention may be applied to the manufacture of formaldehyde from methane will now be given, reference being also made to the accompanying drawing which represents more or less diagrammatically 70 a system of apparatus suitable for use in carrying out the process. Gases resulting from a previous operation, contained in gasometer 11, are mixed with fresh gases in mixing chamber 1, namely, methane, chlorine and oxygen, said fresh gases being introduced through the correspondingly designated valve-controlled pipes as shown on the drawing. In the mixing chamber 1, the gaseous (i. e. gaseous or vaporous) mixture is preheated to a requisite temperature and then enters reaction chamber 2 containing a catalyst. This reaction chamber is maintained at a predetermined temperature of reaction by any suitable heating means 80 (not shown). In practice it is found that temperatures within the range of from about 400° C. to 500° C. are most favorable. The heated products of reaction are cooled in the cooling pipe 3, and the resultant water, together with products that are soluble in it, including much of the formaldehyde, collect in a receiver 4. The residual cooled gases are then scrubbed with water in an absorption tower 5, filled with coke or 90 other suitable material. The water from tower 5 collecting in receiver 6, together with the condensate collecting in receiver 4, is worked up for its formaldehyde and hydrochloric acid content. The gases 100 leaving the top of tower 5 are conducted into another tower 7 where they are dried by means of concentrated sulphuric acid or other suitable drying agent. The dried gases then pass into a reaction chamber 8 105 containing a catalyst for oxidizing any carbon monoxid to dioxid, suitable catalysts for this purpose being cobalt sesquioxid or mixtures of copper and manganese oxids. After passing through reaction chamber 8, 110 the gases are next conducted to and through another absorption tower 9 where they are exposed to milk of lime, or sodium or potassium carbonate, to remove the carbon dioxid content. A suction blower 10 pulls the residual gases from this tower 9 and directs them to gasometer 11 from which they are led back as needed to mixing chamber 1, thus 115 completing the circuit.

It is to be understood that the application 120 of legends to the drawings is not intended to be in any sense restrictive, but is made only for the purpose of rendering still clearer the specific embodiment of the invention chosen to illustrate the broad principles involved.

The oxygen employed may be either the pure gas or air, or mixtures of these in any suitable proportions; but it is advantageous to use pure oxygen because, among other

dling large volumes of inert gases. It is also to be understood that the methane or other hydrocarbon employed may be either the pure gas or may be accompanied by other hydrocarbons. Natural gas may be used to furnish methane for the process. Instead of introducing free chlorine into the mixing chamber, hydrogen chlorid may be introduced, it being only necessary to provide chlorine in available or reactive form, under the conditions of operation.

While it has been found that a much greater percentage conversion of methane to formaldehyde is possible in the present process than has been obtained heretofore by the action of oxygen alone, yet even in the present process there is a practical limit beyond which the proportion of gas entering into reaction may not be profitably pushed, for in higher concentrations a point of equilibrium is reached where the formaldehyde decomposes as fast as it is formed. For this reason it is of great advantage practically to carry out the reactions cyclically as described, and to subject to the action of the catalyst a second time the gases that previously passed through unchanged, removing the products of oxidation by absorption in suitable media and making up the losses by additions of fresh gases.

A variety of different catalysts are available for use in carrying out the process of the invention, where a catalyst is necessary or desirable, as is usually the case. In general, metallic oxids or halids are suitable; but some that are good catalysts for the conversion of methyl chlorid into formaldehyde are less effective in the oxidation of hydrogen chlorid or are apt to cause too energetic oxidation of formaldehyde. More stable or fixed chlorids are distinctly better catalysts in the present process, especially the fixed halids of divalent metals of the alkaline earth group. The chlorids of calcium, barium and strontium are particularly effective catalysts for the purposes of the present invention, and of these, barium chlorid is ordinarily most satisfactory. The alkaline earth metal chlorids are most effective as catalysts in the present process when the temperature and reaction chamber is maintained at from 400° to 500° C. At such temperatures they are very effective in aiding conversion of methyl chlorid into formaldehyde in the presence of oxygen and methane, and at the same time they assist in the oxidation of most of the hydrogen chlorid to chlorine which is at once absorbed by the methane present to form methyl chlorid. As between the oxids and the chlorids, the chlorids afford some advantage in that they have less tendency than the oxids to cause destructive decomposition of the desired hydrocarbon oxidation product sought. Generally speaking, non-vola-

tile chlorids of divalent metals are most desirable, and of these, those which are the most resistant to hydrolysis are the best. Barium chlorid gives the highest yield of formaldehyde and the smallest amount of residual hydrogen chlorid. Although the chlorids of calcium, strontium and barium are most efficient for carrying out all three reactions given above at the same time, other materials, such as the oxids of beryllium and magnesium are also active for the separate oxidation of methyl chlorid to formaldehyde. For the purposes of the present disclosure, reference to a halid or oxid of a divalent element as a catalyst in practicing the invention is to be understood as signifying that compound of a divalent element used as a catalyst which results from continued action of the reacting gases at the reacting temperature upon the oxid of said element. In the case of barium, calcium or strontium, for example, such resultant compound will be the chlorid under the particular reacting conditions hereinafter set forth; while with beryllium or magnesium it will be the oxid. Any well known or suitable way may be resorted to for bringing a large surface of the catalyst into contact with the gas mixtures, such as deposition upon asbestos, pumice or other porous material, whether it is a catalyst or not; for in this process, as well as others employing catalysts, the effective catalytic activity of any of the materials used depends in large measure upon the extent of the surface exposed to the gases.

As already pointed out, it is not advisable from an economic standpoint to attempt to push the percentage conversion of the methyl chlorid into formaldehyde too far in a single passage of the gaseous mixture in contact with the catalyst. In the practice of the invention, therefore, it is best to operate at what may be determined to be the most economical conversion rate and to re-pass the mixture repeatedly in contact with the catalyst in the reaction chamber cyclically, the gases traveling in a circuit. In thus operating, the resultant formaldehyde is removed from the reaction gases after each pass, as well as water, residual hydrogen chlorid, etc.; and at a later point in the circuit fresh methane, chlorine and oxygen are introduced in such quantities as may be necessary to restore substantially the original proportions of the gases in the mixture passed over the catalyst, and to maintain the production of formaldehyde reasonably constant. As chlorine combines very readily and quantitatively with the methane under the conditions herein set forth to form methyl chlorid, the gaseous mixture supplied to the reaction chamber 2 can be considered for all practical purposes to consist of methyl chlorid, methane and oxygen

in predetermined proportions. There should be a large excess of methane in order that the chlorine regenerated by oxidation of the hydrogen chlorid split off from the methyl chlorid may immediately re-combine with more methane to form methyl-chlorid. Accordingly, in a practical embodiment of the novel process which has given good results, the proportions of the gases in the mixture supplied to the catalytic reaction chamber are so adjusted by regulating the feed of fresh gases that the mixture consists of four parts of methane, one part of oxygen, and one part of methyl chlorid or its equivalent in methane and available chlorine, all parts being by volume. Passing this mixture over powdered barium chlorid at about 480° C., and allowing the mixture to contact with the catalyst for a sufficient time, say for 5 seconds or thereabouts by way of example, converts in one passage between 8 and 10 per cent of the methyl chlorid to formaldehyde, while at the same time to a somewhat larger proportion of the methyl chlorid is oxidized to carbon monoxid and carbon dioxid. Comitantly the hydrogen chlorid liberated by oxidation of the methyl chlorid is oxidized to chlorine which, combining with the excess of methane present, regenerates methyl chlorid. In normal practical working of the process under the conditions assumed in this specific example, all of the hydrogen chlorid is oxidized with the exception of an amount equal to about 0.85 per cent of the methyl chlorid content of the gaseous mixture supplied to the reaction chamber; so that the loss of available chlorine in each pass is comparatively slight even if the hydrochloric acid collected with the formaldehyde removed from the effluent gases be allowed to waste.

After the described catalytic oxidation of carbon monoxid to carbon dioxid, if this be necessary, and the removal of the carbon dioxid, the gaseous mixture sent by the blower 10 back to the reaction chamber by way of the gasometer 11 therefore still consists of methane, oxygen and methyl chlorid but in proportions differing from those of the original mixture due to the oxidizing reaction and the small loss of chlorine as hydrochloric acid. By properly adjusting the feed of fresh methane, oxygen and chlorine into the system, in advance of the mixing and reaction chambers, the original proportions of the gases may be approximately restored and, the other conditions of operation being maintained uniform, the output of formaldehyde can be kept substantially constant at the rate found to be the best for profitable operation of the process.

The isolation of the formaldehyde which is condensed and absorbed, together with water and hydrochloric acid, from the cir-

culating gases after passage through the reaction chamber, may be effected in any well known or suitable manner. One practical way, where the acid content of the condensate is sufficiently high is to precipitate the formaldehyde as paraformaldehyde by subjecting the mixed liquid condensate to a low temperature, adding salt as may be necessary to lower the freezing point of the fluid to a point at which the polymerization and precipitation is rapid. If it is found desirable to recover the hydrochloric acid present in the aforesaid condensate, the filtrate from the polymerized formaldehyde precipitate may be dehydrated with concentrated sulfuric acid and the hydrogen chlorid reintroduced into the circulating gases. Under ordinary commercial conditions, however, the relatively small proportion (e. g. 10%) of hydrogen chlorid escaping re-conversion to methyl chlorid in the normal operation of the process in its more efficient forms can be otherwise more economically replaced.

Other halids such as the iodid or bromid may be used instead of, or in conjunction with, methyl chlorid; but experience thus far has shown the chlorid to be far the most advantageous and its use is therefore to be recommended in practice.

In the treatment of more complex hydrocarbons than methane, the production and recovery of any single intermediate oxidation product is sometimes rendered more difficult by reason of the possibility of halogen substitution in different positions in the molecule, thus rendering the production of mixtures of oxidation products likely. This is of course unobjectionable where the production of a single oxidation product is not essential. In the case of homologues close to methane, the liability to production of mixtures of oxidation products is not so pronounced and it is feasible, for example, to prepare acetaldehyde from ethane by the present process.

What I claim is:

1. In the manufacture of partial oxidation products of hydrocarbons, the process which comprises heating a gaseous mixture of a hydrocarbon, available oxygen and an available halogen in a suitable reaction chamber to temperatures favoring limited oxidation of the hydrocarbon, and separating a desired oxidation product of said hydrocarbon from the reaction gases leaving said chamber, at least a substantial portion of said halogen being made available in the oxidation and again used for reaction with further quantities of said hydrocarbon.
2. The process set forth in claim 1, further characterized by the employment in the reaction chamber of a catalyst favoring oxidation under the conditions prevailing in said chamber.
3. In the manufacture of aldehydes, the

process which comprises halogenating a hydrocarbon to obtain a mono-halogen derivative thereof, and oxidizing the resultant mono-halogen derivative to obtain the desired aldehyde.

4. In the manufacture of aliphatic aldehydes, the process which comprises halogenating an aliphatic hydrocarbon to obtain a mono-halogen derivative thereof, and oxidizing the resultant mono-halogen derivative to obtain the desired aldehyde.

5. In the manufacture of formaldehyde, the process which comprises halogenating methane to obtain methyl halide and oxidizing resultant methyl halide to formaldehyde.

6. In the manufacture of formaldehyde, the process which comprises chlorinating methane to methyl chlorid and oxidizing such methyl chlorid to formaldehyde.

7. In the manufacture of formaldehyde, the process which comprises halogenating methane to obtain methyl halide and oxidizing resultant methyl halid to formaldehyde in the presence of a catalyst favoring concomitant oxidation of resultant hydrogen halid and liberation of the halogen.

8. In the manufacture of formaldehyde, the process which comprises halogenating methane, oxidizing resultant methyl halid to formaldehyde, and oxidizing resultant hydrogen halid to render the halogen available, all these reactions being effected substantially simultaneously in the presence of a catalyst comprising a reaction-promoting compound of a divalent element, removing formaldehyde, and utilizing the resultant available halogen to halogenate more methane.

40 9. In the manufacture of formaldehyde, the process which comprises heating to a reacting temperature a gaseous mixture comprising methyl halid, methane and oxygen, and recovering formaldehyde from the resultant reaction gases.

45 10. In the manufacture of formaldehyde, the process which comprises heating to a reacting temperature a gaseous mixture comprising methyl chlorid, methane and oxygen, and recovering formaldehyde from the resultant reaction gases.

50 11. In the manufacture of formaldehyde, the process which comprises heating to a reacting temperature a gaseous mixture comprising methane, methyl halid and oxygen, in the presence of a catalyzer for the oxidation of hydrogen halid, separating resultant formaldehyde, adding more methane and oxygen to the residual mixture of gases, and repeating the heating operation and the separation of formaldehyde, cyclically.

55 12. In the manufacture of formaldehyde, the process which comprises heating to a reacting temperature a gaseous mixture comprising methane, methyl chlorid and oxygen

in the presence of a catalytic compound of an alkaline earth metal, said methane being present in larger volume than either of the other gases, separating resultant formaldehyde from the reaction gases, and re-treating the residual gases for production of more formaldehyde.

70 13. In the manufacture of formaldehyde, the process which comprises heating a gaseous mixture comprising methyl chlorid and oxygen to an oxidizing temperature at which formaldehyde can exist, and recovering resultant formaldehyde.

75 14. In the manufacture of formaldehyde, the process which comprises reacting upon methyl chlorid with oxygen at a temperature within the approximate range of 400° C. to 500° C., and recovering resultant formaldehyde.

80 15. In the manufacture of formaldehyde, the process which comprises passing a mixture containing predetermined proportions of methane, methyl chlorid and oxygen over a catalytic compound of an alkaline earth metal at a temperature within the approximate range of 400° C. to 500° C., separating formaldehyde from the effluent gases, adding methane, oxygen and available chlorine to the residual gases as may be necessary to restore approximately the original proportions of methane, methyl chlorid and oxygen, and repeating the foregoing operations for production of more formaldehyde in a continuous cyclical procedure.

85 16. In the manufacture of formaldehyde, the process set forth in claim 15, further characterized by the fact that the catalytic compound employed is a reaction-promoting compound of an alkaline earth metal.

90 17. In the manufacture of formaldehyde, the process set forth in claim 15, further characterized by the fact that the catalytic compound employed is barium chlorid.

95 18. In the manufacture of formaldehyde, the process set forth in claim 15, further characterized by the fact that the catalytic compound employed is barium chlorid and that the reaction temperature is maintained at about 480° C.

100 19. In the manufacture of formaldehyde, the process set forth in claim 15, further characterized by the fact that the mixture passed over said catalytic compound comprises about four parts methane, one part methyl chlorid and one part oxygen, by 115 volume.

105 20. In the manufacture of partial oxidation products of hydrocarbons, the process which comprises halogenating a hydrocarbon in heated gaseous condition and oxidizing the resultant halogen derivative to split off hydrogen halid and form the desired oxidation product.

110 21. In the manufacture of partial oxidation products of hydrocarbons, the process

- which comprises halogenating a hydrocarbon in heated gaseous condition in the presence of available oxygen and of a catalyst aiding oxidation of hydrogen halid, an excess of said hydrocarbon being also present, and separating a desired oxidation product from the reaction gases.
22. In the manufacture of partial oxidation products of paraffin hydrocarbons, the process which comprises halogenating and oxidizing a paraffin hydrocarbon in gaseous condition with the aid of a catalyst comprising a reaction-promoting compound of a divalent element.
- 10 23. In the manufacture of partial oxidation products of paraffin hydrocarbons, the process which comprises chlorinating and oxidizing a paraffin hydrocarbon with the aid of a catalyst comprising barium chlorid.
- 15 24. In the manufacture of formaldehyde, the process which comprises halogenating and oxidizing methane with the aid of a catalyst comprising a reaction-promoting compound of a divalent element.
- 20 25. In the manufacture of formaldehyde, the process which comprises chlorinating and oxidizing methane with the aid of a catalyst comprising barium chlorid.
26. In the manufacture of formaldehyde, the process which comprises heating a gaseous mixture comprising methyl chlorid and oxygen to an oxidizing temperature at which formaldehyde can exist, in the presence of a catalyst comprising a reaction-promoting compound of a divalent element, and recovering resultant formaldehyde.
27. In the manufacture of formaldehyde, the process which comprises reacting upon methyl chlorid with oxygen at a temperature within the approximate range of 400° C. to 400° C. in the presence of a catalyst comprising a reaction-promoting compound of a divalent element, and recovering resultant formaldehyde.

In testimony whereof I hereunto affix my 45
signature.

FRANCIS J. CARMAN.
